[57] CLAIM

The ornamental design for a cutlery block with spice rack, as shown and described.

DESCRIPTION

FIG. 1 is a side, top perspective view of a cutlery block with spice rack showing our new design, the knife blade receiving shots are shown in broken lines for illustrative purposes only and no part of the claimed design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 9 is a front elevation view thereof;

FIG. 10 is a top plan view thereof; and,

FIG. 11 is a left side elevation view thereof, the spice jars are shown in broken lines for illustrative purposes only and form no part of the claimed design.
